UNITED STATES PATENT OFFICE.

LÉOPOLD DARIMONT, OF BRUSSELS, BELGIUM.

MICROPHONE.

Application filed October 4, 1924. Serial No. 741,661.

To all whom it may concern:

Be it known that I, LÉOPOLD DARIMONT, a subject of the King of the Belgians, and resident of Brussels, Belgium, have invented 5 certain new and useful Improvements in Microphones, of which the following is a specification.

My present invention has for its object a useful improvement in microphones for 10 telephonic plants, and more particularly in microphones wherein the vibrations of a vibrating plate are transmitted by means of balls of different sizes arranged between the two poles, the whole being enclosed within a suitable housing. The said improvement consists of such an arrangement of the 15 balls that the large balls arranged between the poles form constant contacts between them, whilst the small balls or grains are arranged in the interstices between the large 20 balls and of such sizes that they will be completely movable in said interstices, said arrangement producing two different effects of variation of resistance in the michophonic 25 circuit which will be produced simultaneously and therefore added to each other to permit the transmission of vocal vibrations and musical vibrations simultaneously, that is the natural transmission of the human voice. 30 One embodiment of my invention is illustrated by way of example in axial longitudinal section in the accompanying drawing.

The improved microphone comprises a 35 suitable housing or casing, such as cylinder 1 made of celluloid, which contains the two poles 2 and 3, made of carbon or any other suitable material.

The pole 2 is attached to the base 1^a of 40 the cylinder and surrounded by a conducting wire 2^a extending through said cylinder. The pole 3 is attached to a screw-threaded bolt or rod 5 screwed into the base 1^b of the cylinder and provided with a key-slot 45 5^a to enable the pressure produced between the two poles to be adjusted. Said rod is also provided with a nut 5^a serving to attach the conducting wire 5^b and hold the pole 3 in its adjusted position. Arranged between 50 the poles 2 and 3 are balls of carbon or any other suitable material. Said balls are of different sizes: the larger ones 6 are placed directly between the two poles, and form constant contacts between them. Arranged 55 in the interstices between them are smaller balls or grains 7 and 7^a, the diameter of

which is such that they will be freely movable in said interstices.

The whole, namely the cylinder, poles 2 and 3, balls 6, 7 and 7^a etc., form one unit 60 which may be set into contact with any vibratory material to reveal the vibrations thereof, and in the present example, the same is attached directly or by means of an intermediate part 1^c to a vibrating plate 8. 65

Said vibrating plate is held in a suitable protecting casing 10 by means of rings 9 and 9^a, the whole being assembled and attached by means of a screw-threaded ring 11 screwed onto the part 10^c, whilst the opposite end of the casing is closed by means of a cover-plate 12 screwed onto the part 10^a. 70

The conducting wire 2^a extends through the casing at 10^a where insulating material is provided to this end, whilst the conducting 75 wire 5^a is soldered to the casing at 10^a and extended by the external wire 5^c soldered at 10^b to the casing, if the latter is made of metal. Otherwise the conducting wire 5^a extends through an insulator secured in said 80 casing, to the outside of the latter.

Said wires 2^a and 5^c are connected to a telephonic circuit comprising a battery, a receiver, etc.

A wire-gauze 13 may be secured to the 85 ring 11 to protect the vibrating plate.

The variations in resistance of the microphonic circuit of the device described are due to two different effects of sensitiveness, which will be produced simultaneously and the results of which will be added. The first effect is due to the arrangement of large balls forming constant contacts between them, which results in the possibility of the transmission of the voice. The second effect 95 is due to the jolting of the movable grains in the interstices between the large balls. Said jolting produces very sharp variations in the coherence between said small balls or grains and said large balls, which produces 100 a second series of variations in the microphonic circuit more intensive and particularly more abrupt permitting the transmission of musical vibrations, whereas the same would not be convenient for the transmission 105 of vocal transmissions (owing to said too sudden vibrations). The two effects will be produced simultaneously and the results thereof will be added. The final result thereof will be the transmission of the voice 110 with all its tones, whereby it will be rendered natural.

- The microphonic cylinder forming a unit may be used for amplifying the scarcely revealable vibrations in wireless telegraphy at the receiving stations by applying the same 5 at the place where said vibrations are produced. It is obvious that constructional modifications may be made in the microphone described without departing from the scope of the invention. I may for instance 10 combine several units and arrange the same either side by side or one above the other, and the cylinders 1 may be placed upon the vibrating plate in any other convenient manner.
- 15 Having now fully described my said invention, what I claim and desire to secure by Letters Patent, is:
1. In a microphone, the combination with a suitable container, and poles arranged at 20 opposite ends thereof, of a plurality of large balls placed directly between said poles and

forming constant contacts between them, a plurality of small balls or grains placed in the interstices between said large balls and freely movable therein, and suitable connections to any desired telephonic circuit, substantially as set forth. 25

2. In a microphone, the combination with a suitable container, poles arranged at opposite ends thereof, and means for adjusting 30 one of said poles, of a plurality of large balls placed directly between said poles and forming constant contacts between them, a plurality of small balls or grains placed in the interstices between said large balls and 35 freely movable therein, and suitable connections to any desired telephonic circuit, substantially as set forth.

In testimony whereof I have hereunto set my hand.

LÉOPOLD DARIMONT.
